UNITED STATES PATENT OFFICE.

THOMAS A. MATTHEWS, OF NASHVILLE, TENNESSEE.

ENVELOP OR CARD DELIVERING CABINET.

SPECIFICATION forming part of Letters Patent No. 748,966, dated January 5, 1904.

Application filed June 1, 1903. Serial No. 159,585. (No model.)

To all whom it may concern:

Be it known that I, THOMAS A. MATTHEWS, a citizen of the United States, residing at Nashville, Davidson county, Tennessee, have 5 invented certain new and useful Improvements in Envelop or Card Delivering Cabinets, of which the following is a specification.

My invention relates to that class of cabinets provided with means for delivering envelopes, cards, tags, and the like.

The objects of the invention are to provide a novel and effective means for feeding the flat articles one at a time from the cabinet, to provide a novel automatic mechanism for 15 moving the stack of envelopes or articles forwardly as the same decreases in size by the successive removal of the articles, and to provide a novel mechanism for regulating the amount of such movement. These objects I 20 accomplish by the construction illustrated in the accompanying drawings, in which—

Figure 1 is a perspective of a cabinet containing my improvements. Fig. 2 is a horizontal section on line 2 2, Fig. 4. Fig. 3 is 25 an enlarged perspective of the operating parts from the rear. Fig. 4 is a longitudinal section on line 4 4, Fig. 2. Fig. 5 is an enlarged detail view of the mechanism for feeding the envelopes or the like out of the cabinet. Fig. 30 6 is a detail sectional view showing the flap at the discharge-opening.

A designates the cabinet, which may have suitable drawers a_1 and an advertising-space a' . The top of the cabinet has a sliding or 35 other suitable cover A', through which the articles to be served may be placed in the cabinet. At one side of the cabinet is a sliding panel A².

The front end of the cabinet is vertically 40 slotted for the passage and the working of the operating-arm B of the vertically-reciprocating carrier or slide B', guided between the guides b b on the inner side of the cabinet. This carrier or slide is suspended from the 45 contractile springs c c, secured at their upper ends to a cross-piece a^2 and at their lower ends secured to said carrier, which is preferably made hollow to inclose the springs, as shown in Fig. 3.

50 D is a yoke-like arm pivoted at its upper end to the rear extension b' of the carrier B', and the roller D' is mounted in this arm to be

moved up and down with the carrier B'. The arm D is pressed rearwardly, so as to throw its roller D' against the front envelop or card 55 of a vertically-disposed pack E by means of a plate-spring D², which bears against a cross-bar d (see Fig. 3) and may be adjusted by its retaining-screw d³. The lower end of this swinging arm D is steadied by means of side 60 arms d' d', pivoted at their rear ends to the lower end thereof and pivotally and slidably connected at their forward ends to the carrier B' by pins and slots d² d³. The arms d' d' are connected rigidly by a cross-piece 65 d⁶. The roller D', which is preferably of rubber or covered with some frictional surface, is provided at one end with a ratchet d⁴, engaged by a spring stop-pawl d⁵, the teeth of the ratchet being so arranged as to allow the 70 roller D' to turn freely as it travels downwardly, but hold it against rotation as it is moved upwardly, so that it will slide the front article E up through a slot a⁵ in the top of the cabinet, said slot being covered by a flap a⁶, 75 which will prevent more than one article E passing out through the slot. In its upward movement the front envelop bears against a loose roller a⁷ just below the front wall of said slot.

The pack of envelopes or the like is supported at the rear by a vertical pack-adjusting slide F, having a lower horizontal member F' extending under the pack and guided at its side edges in the guideways g g at the 85 upper edges of two parallel bars G G, extending along the bottom of the cabinet.

H H' are two brackets mounted, respectively, at the front and rear ends of the cabinet bottom, and J is a stationary rack fixed 90 at its ends to said brackets.

F² is a pawl pivoted to the slide F and made in the form of a loop, with its lower cross-piece engaging the rack J tooth by tooth as the slide F moves forwardly, and thus preventing accidental reverse movement of the 95 slide.

K is a double rack mounted to slide in the brackets H H' beneath the upper rack J and against the action of a spring k, and this 100 double rack K is engaged by a spring-pawl F³, carried by the slide F, so that as the rack K is moved rearwardly its teeth will pass the pawl F³; but when rack K is moved forwardly

it will positively engage pawl F^3 and pull the slide F against the pack and move it toward roller D' just sufficient to take up the space due to the removal of one or more of the envelopes.

The rack K is given such forward movement from a bell-crank lever k^2 , connected to its front end by links k^3 , the bell-crank lever being in turn connected to the lower end of a vertically-reciprocating operating-rod K' by means of a link k^4 . The operating-rod K' is connected by a pin k^5 to the vertically-slotted forward arm h of bracket H . The rod K' has an upper extensible member K^2 sliding therein and provided with notches k^6 , engaged by a pawl k^7 or other suitable adjusting device. By raising or lowering the member K^2 the throw of the rack K may be regulated. This operating-rod $K' K^2$ is arranged below and in the downward path of the cross-bar d^6 , whereby when the carrier is moved down the cross-bar will strike the said operating-rod and actuate the take-up slide F . Should the pack E be pressed a little hard against the roller D' , it will yield, and the arms d' will slide forwardly until the cross-bar d^6 is out of the vertical plane of the operating-rod K' , and so the feed of the pack will cease for awhile, and as the pack loosens up the roller D and arms d' will resume normal position. After the pack E is exhausted panel A^2 may be opened and the operator's hand introduced to move the slide F back to the starting-point.

The cabinet having been filled with a pack E of the desired size it is only necessary to press the operating-arm B down to lower the roller D' , which now runs free to the position shown in Fig. 4, and then upon releasing the said arm the springs c will quickly raise the carrier B' and the roller D' , which being now locked will engage the front article of the pack and push it up through the slot, as shown in Figs. 1 and 6, where it may be grasped and drawn out. I also provide the following alarm mechanism: a gong L , an angular bell-hammer arm L' , pivoted above the carrier B' , and there provided with a crank L^2 , which will be struck every time the carrier is elevated by its springs c .

50 5. What I claim is—

1. The combination with a cabinet for envelopes and the like having a discharge-slot in its top, of a vertically-reciprocating carrier or slide mounted in one vertical wall of the cabinet, a roller carried by the slide and free to roll in its downward movement along the front of the vertically-disposed pack, means for locking the roller when the carrier moves upwardly to thereby push the front envelop 55 or article through the slot and a spring pressing the roller rearwardly toward the pack, and means for automatically pressing the pack toward the roller.

2. The combination with a cabinet for envelopes or the like, having a discharge-opening in its top, of a vertically-reciprocating carrier, a swinging arm pivoted at its upper

end to the carrier, a roller mounted on the lower end of said arm and free to rotate as the carrier moves down, a pawl and ratchet to lock the roller when it moves upwardly to slide an envelop or the like through the slot, a spring pressing the roller-carrying arm rearwardly toward the pack, and means actuated from the carrier to feed the vertically-disposed pack intermittently toward the roller.

3. The combination with the cabinet having an opening for the discharge of the envelopes or the like, of a vertical-reciprocating slide, a roller mounted on the slide and free to roll down the pack and having means to lock it in its opposite or feeding movement, a slide at the rear of the pack to feed it toward the roller, a rack-and-pawl mechanism for moving the slide forwardly, and means for actuating the rack from the carrier.

4. The combination with the reciprocating carrier having a feed device to feed the envelopes or the like, of a slide for moving the pack toward the feed device, means for operating the slide including an operating-rod actuated from the carrier in its downward movement.

5. The combination with the reciprocating carrier and the feed device thereon, of a slide movable at right angles to the carrier to move the pack toward the feed device, a reciprocating spring-pressed rack, a pawl on the slide engaging the rack, a reciprocating operating-arm connected to the said rack and actuated from the carrier.

6. The combination with the pack-feeding slide having a stop-pawl and rack therefor, a reciprocating feed-rack for the slide, a pawl on the slide engaging the feed-rack, and a vertically-reciprocating operating-rod connected to the feed-rack, of a feed mechanism to feed out the front article of the pack and constructed to actuate the said operating-rod.

7. The combination with the pack-feeding slide having a stop-pawl and rack therefor, a reciprocating feed-rack for the slide, a pawl on the slide engaging said feed-rack, and a vertically-reciprocating operating-rod connected to the feed-rack and having an adjustable or extensible member, of a feeding mechanism to feed out the front article of the pack and constructed to actuate the said operating-rod.

8. The combination with the reciprocating carrier a spring-pressed arm carried thereby a roller journaled on the lower end of said arm horizontal sliding arms connecting the roller-carrying arm with its slide and provided with a cross-bar, and means for locking said roller in its upward or feeding movement, of a pack-feeding slide, a pawl-and-rack mechanism for moving the slide toward the feed-roller, a vertically-sliding operating-rod for the feed-rack located below the said cross-bar to be actuated thereby when the carrier is pressed down.

9. The combination with the spring-retracted carrier having an operating-arm, a

yieldingly-supported roller carried by the slide and free to rotate in one direction and held from rotation in the feeding movement, a bell-hammer having a cranked arm in the 5 path of the slide and a bell or gong, of a pack-feeding mechanism having an actuating-arm operated from the carrier.

10. The combination in a cabinet with the vertically-reciprocating carrier and the feed device carried thereby, supporting-springs secured to the cabinet and to the slide to re-

turn it to its normal position, of a bell, and a bell-hammer having an arm provided with a crank lying in the upward path of the carrier.

15 In testimony whereof I affix my signature in presence of two witnesses.

THOMAS A. MATTHEWS.
